CHRONOCOMPARATOR MACHINE

Jean-Pierre Bonny, La Chaux-de-Fonds, Switzerland, assignor to PORTESCAP, Le Porte-Echappement Universal S.A., La Chaux-de-Fonds, Switzerland

Filed Dec. 13, 1968, Ser. No. 14,957

Term of patent 14 years

Int. Cl. D10—11

U.S. Cl. D52—6

FIG. 1 is a perspective view showing the front, top and one side of a chronocomparator machine showing my new design; and

FIG. 2 is an elevational view of the other side of the machine shown in FIG. 1.

The top rear surface of the chronocomparator in these figures showing my new design is planar, and the rear wall is substantially plain in appearance.

The dominant features of my design reside in the portions shown in the full lines in the drawings.

I claim:

The ornamental design for a chronocomparator machine, substantially as shown and described.
